UNITED STATES PATENT OFFICE.

FRED. N. PEPPERLING, OF STUART, NEBRASKA.

DRAG-SAW.

SPECIFICATION forming part of Letters Patent No. 374,994, dated December 20, 1887.

Application filed July 19, 1887. Serial No. 244,762. (No model.)

To all whom it may concern:

Be it known that I, FRED. N. PEPPERLING, a citizen of the United States, residing at Stuart, in the county of Holt and State of Nebraska, have invented a new and useful Improvement in Drag-Saws, of which the following is a specification.

My invention relates to improvements in fire-wood drag-saws; and it consists in certain novel features, hereinafter described and claimed.

In the accompanying drawings, which fully illustrate my invention, Figure 1 is a perspective view of my improved machine; and Figs. 15 2 and 3 are side elevations of the same, taken from opposite sides. Fig. 4 is a detail view.

Referring to the drawings by letter, A A designate two similar standards erected upon a common sill or base piece, B, adapted to rest 20 upon the ground and connected at their upper ends, as shown.

C designates a bar hinged at one end to the upper ends of the standards and provided at its opposite end with the depending plate D, 25 having a central vertical slot, E, and provided with the pivoted teeth F near its lower end on opposite sides of the said slot. The bar C is provided with a central longitudinal slot, G, for a purpose hereinafter set forth. One of the 30 standards A is provided at its upper end with an upward extension, H, and to the side of the said standard and the end of the extension I secure a bracket or keeper, I, having a series of notches, J, along its rear edge. Through 35 this keeper or bracket I pass a lever, K, one end of which is pivoted to the hinged bar C about centrally of the same, and the other end of which projects from the keeper and is provided with a catch which normally engages 40 one of the notches J. This catch comprises a sliding plate, L, held to the under side of the lever K, the handle M, connected to the sliding plate and pivoted to the lever K, and the spring N, secured to the under side of the lever and 45 bearing on the handle to depress the same and throw the sliding plate into engagement with one of the notches J. This lever K is provided with a horizontal longitudinal slot, O, about midway its ends, and the end of a crank-arm, P, 50 is fitted in this slot. This crank-arm P forms one end of a rock-shaft, which is journaled on

top of the hinged bar C near one end of the longitudinal slot G therein, and Q designates an arm or lever, which projects upward from the end of the rock-shaft opposite the crank-arm 55 P. R is a cord which has one end secured to the upper end of the arm or lever Q and extends therefrom over a pulley, S, journaled in the upper end of a bracket, T, secured to the lever K near the pivoted end of the same, and thence down through the slot G to the pitman U, to which it is secured near the end of the same. The saw V is secured to the front end of this pitman U and extends therefrom through the slot E in the plate D. The rear end of the 60 pitman U is projected between the standards A A and mounted on the cranked portion W of the shaft X, which is journaled in the rear sides of the standards and projects past the same, one end being provided with the crank- 65 handle Y and the other end having a gear-wheel, Z, mounted thereon.

A' is a gear-wheel journaled below the gear-wheel Z and meshing therewith, and B' designates a fly-wheel mounted on the same shaft 70 as the gear-wheel A' and serving to give the machine a smooth and easy motion.

C' designates a longitudinally-slotted bar or plate pivoted to the side of one of the standards A and adjustably secured to the hinged bar C 75 by means of a thumb-screw, D', as shown.

The operation of my device will be readily understood. The machine is placed in position with the saw resting on the log and passing through the slotted plate D. The teeth F 85 are then forced into the log and the log thereby held from rolling. The crank-handle Y is then turned so as to reciprocate the pitman U and thereby draw the saw back and forth across the log. As the saw advances through the log 90 the lever K is raised, so that the pitman will be lowered, and thus kept at all times in the proper position to prevent buckling of the saw. The hinged bar C can be readily adjusted by means of the slotted bar C' and thumb-screw 95 D' to different heights, so that the teeth F can be readily forced into logs of various diameters.

It will be observed that my device is composed of few parts and is very simple in construction, and it is thought that its advantages 100 will be readily appreciated.

Having thus described my invention, what I

claim, and desire to secure by Letters Patent, is—

1. The combination of the standards, the bar C, hinged thereto, the saw arranged below the 5 said bar, the lever K, pivoted to the said bar and adjustably held to the standard, the rock-shaft mounted on the bar C, and the crank-arm P and lever Q, formed on opposite ends of said shaft, the crank-arm being fitted in a longitudinal slot in the lever K and the lever Q being connected with the saw, substantially as specified.

2. The combination of the standards, the bar C, hinged thereto, the saw arranged below said 15 bar, the slotted lever K, pivoted to said bar and adjustably held to the standards, the rock-

shaft mounted on the bar C, the crank-arm P and the lever Q, formed on opposite ends of said shaft, the arm P, fitting in the slot of the lever K, the pulley S, carried by a bracket, T, 20 on the lever K, and a cord, R, passing over the pulley S and having its opposite ends secured to the lever Q and connected to the saw, substantially as specified.

In testimony that I claim the foregoing as 25 my own I have hereto affixed my signature in presence of two witnesses.

FRED. N. PEPPERLING.
